LASTING MACHINE

Napoleon A. Monfils, Haverhill, and Edward Quinn, Saugus, Mass., assignors to United Shoe Machinery Corporation, Flemington, N. J., a corporation of New Jersey

Application October 17, 1946, Serial No. 703,774

12 Claims. (Cl. 12-1)

1

This invention relates to lasting machines, and more particularly to a machine for lasting with an adhesive. It will be understood, however, that certain features of the invention are not limited to use in a machine for lasting with adhesive or in a machine of the exact construction herein illustrated.

An object of the invention is to provide a novel and improved machine for lasting with adhesive which is of relatively simple and inexpensive construction yet effective and dependable in operation. With this end in view, the herein illustrated machine is provided with novel frictionally acting means for continuously and progressively tensioning successive portions of the stock to be lasted, in a direction heightwise of a shoe, for drawing the lasting margin thereof inwardly from the edge of, and over, the bottom of the shoe and for exerting a stress thereon tending to feed the shoe; together with means for pressing the lasting margin of the tensioned stock against the bottom of the shoe. More particularly, and in accordance with a feature of this invention, novel tensioning and overdrawing means comprise a driven roll mounted for rotation about an axis substantially perpendicular to the portion of the bottom of the shoe being operated upon and provided with a smooth-surfaced helical rib and a sleeve having an arcuate operating surface for yieldingly holding the lasting margin of the stock wrapped around the rib on the roll. The arrangement is such that, as the roll rotates with the lasting margin of the stock yieldingly held against the rib thereon, the stock will be drawn upwardly, in a direction heightwise of the shoe, by the frictionally acting smooth-surfaced helical rib, which also exerts a stress on the stock tending to feed the shoe. The shoe is held in the hands of an operator, who, by permitting it to feed along at different speeds, relatively slower than the peripheral speed of the rib on the roll, may readily vary the tensioning effect to accommodate different operating conditions. Also, because of the manner in which the stock is wrapped around the rib by the arcuate operating surface of the sleeve, the lasting margin of the stock is drawn inwardly from the edge of, and over, the bottom of the shoe.

For pressing the lasting margin of the stock against the bottom of the shoe, the herein illustrated machine is, in accordance with a further feature of the invention, provided with means for imparting a rapid series of hammer blows to the lasting margin for securing it adhesively to the bottom of the shoe. Preferably, and as herein

2

illustrated, this means comprises a hammer which is rapidly reciprocated, during the operation of the machine, and arranged to engage the lasting margin of the stock just as it emerges from between the roll and the sleeve.

The above and other objects and features of the invention will be apparent from the following detailed description of a preferred embodiment thereof, illustrated in the accompanying drawings, and will be pointed out in the claims.

In the drawings,

Fig. 1 is a view, in side elevation, of a machine embodying the features of this invention;

Fig. 2 is a view, in section on lines II-II of Fig. 3, of a portion of the machine shown in Fig. 1 and illustrating the operating elements thereof at an enlarged scale;

Fig. 3 is a view, in side elevation and at an enlarged scale, of the front end of the machine as seen from the side opposite to that shown in Fig. 1; and

Fig. 4 is a view, in side elevation and at an enlarged scale, of the front end of the machine as viewed in Fig. 1 and showing the operating elements in position to receive the work.

Referring now to these drawings, the operating elements of the machine therein illustrated comprise a tensioning and feeding roll 10, provided with a smooth-surfaced helical rib 12, a sleeve 14, having an arcuate operating surface 16, for holding the lasting margin of stock to be lasted yieldingly against the helical rib of the aforementioned roll, and a vertically reciprocating hammer 18 for pressing the lasting margin of the tensioned stock against the bottom of a shoe. During the operation of the machine, the shoe is positioned in a widthwise direction relative to the roll 10, by means of an edge gage roll 20, and is held against movement vertically, in response to the tension applied to the stock, by means of shoe-bottom rests 22 and 24 and also by the engagement of the lower end of the roll 10 with the bottom of the shoe.

The roll 10 is secured to the lower end of a shaft 30 which is journaled in a block 32. This block is carried by a depending portion 34 of an overhanging arm 36, mounted on the top of a cast head 38, see Figs. 1, 3 and 4. The cast head comprises a lower base portion 40, adapted to rest on a bench or other suitable support, not shown, and is hollow to receive a motor 42. The shaft of this motor is provided with a pulley 44 which drives a double-faced pulley 46 by means of a belt 48. The shaft 30, and the roll 10 carried thereby, are driven from the pulley 46 by means of a belt 50.

and a pulley 51, secured to the upper end of the shaft 30. The belt 50 is trained over a pair of idler pulleys, one of which is indicated by the reference character 52 in Fig. 1 of the drawings. These idler pulleys are each rotatably mounted on a countershaft 54 which is supported by a bracket 56 secured to the top of the head 38 by screws 58.

The sleeve 14 is formed as a downwardly extending portion of a bar 60 which is slidably mounted in a guideway 62, cut in the block 32, and is held in place by means of a cover plate 64, secured to the block 32 by means of screws 66. The bar 60 carries a pin 68 which projects through a slot 70, formed in the cover plate 64, and enters a slot 72, formed in the lower end of a lever 74. This lever is pivoted on a stud 76, see Figs. 1 and 4, and connected to its upper end is a link 78. This link is provided with a cylindrical end portion 79 which passes through a thimble 80, pivotally mounted on the upper end of a second lever 82. A collar 84 is secured to the end portion 79 of the link 78, on one side of the thimble 80, and on the opposite side of this thimble a compression spring 86 is interposed between the thimble and adjusting nuts 88, threaded on the end portion 79. The lever 82 is pivotally mounted on a stud 90, carried by the overhanging arm 36, and a coil spring 92 is stretched between the lower end of this lever and a pin 94 mounted in the upper end of the head 38. Also connected to the lower end of this lever 82 is a cable 96 which passes over a sheave 98, rotatably mounted on a shaft 100 in a bracket 102, carried by the head 38, and down through a hole 104 in the base portion 40 where it is secured to a treadle 106, see Fig. 1.

With the arrangement just described, when the treadle 106 is released, spring 92 will swing the lever 82, in a counterclockwise direction, and, through the action of link 78, the thimble 80 now bearing against the collar 84, will cause lever 74 to swing in the same direction thus to move the bar 60, together with the sleeve 14, to the right and to the open position shown in Fig. 4. These movements of the aforementioned parts are limited by the engagement of the lower end of the lever 74 with a second cover plate 110 which is secured to the first-mentioned cover plate 64 by means of screws 112. Depression of the treadle will move these parts reversely and to the closed position shown in Figs. 1 and 3, a stop 114, adjustably secured to the overhanging arm 36 by means of screws 116, being provided to prevent actual contact of the surface 16, of the sleeve 14, with the helical rib 12 on the roll 10.

When stock, such, for example, as the lasting margin of the cover C of a platform shoe comprising an upper U and platform P, assembled on a last L, is inserted between the roll 10 and the sleeve 14, with these parts in the open position shown in Fig. 4, and the treadle 106 depressed, the lasting margin of the stock will be pressed, yieldingly, against the helical rib 12, on the roll 10, by the arcuate surface 16, by reason of the action of the spring 86. The thimble 80 will now move to the right and away from the collar 79, see Fig. 1, thus compressing the spring 86, and the lever 74 will be held away from the stop 114. As will be apparent, further depression of the treadle will merely cause the spring 86 to yield without materially changing the pressure applied to the stock or causing it to increase to a point where damage to the stock might result. Instead, because of the action of the spring 75

86, a substantially uniform yielding pressure of the stock against the roll is obtained. However, the intensity of this pressure may be varied simply by means of the adjusting nuts 88, or substituting a stronger, or a weaker, spring for the spring 86. If desired, a stop for the treadle may be provided, as shown at 118, 119, in Fig. 1, to limit its downward movement and thus ease the strain on the operator.

The hammer 18 is formed on the end of a bar 120 and is shaped as shown in Fig. 2 to engage the lasting margin of the stock beyond the sleeve 14 in the direction of feed. The bar 120 is slidably mounted in a groove 122 formed in the block 32, and is held in place, by the cover plate 110, see Fig. 4. For reciprocating the bar vertically, it is connected to the end of a lever 124 by means of a pin 126 which passes through a slot 128, in the cover plate 110, and enters a slot 130 in the lever. The lever 124 is pivotally mounted on the stud 90, inside of the lever 82, and to its other end an L-shaped arm 132 is adjustably secured by means of screws 134. The arm 132 carries a cam roll 136 which engages a star cam 138 that is drivingly connected to one of the pulleys 52. A coil spring 140, connected to the lever 124 and also to the overhanging arm 36, holds the cam roll against this cam with the hammer 18 elevated, when the cam is in the position shown in Fig. 1. As the cam rotates, the lever 124 is oscillated at a high speed and thus causes the hammer 18 to impart a rapid series of hammer blows to the lasting margin of the stock.

The edge gage roll 20 is mounted on a bracket 141 which is adjustably secured, by means of screws 142, to a rearwardly projecting ear 144 formed on the sleeve 14, Figs. 2, 3 and 4. The shoe-bottom rest 22 comprises a ball that is rotatably mounted in a socket 146 provided on the lower end of a rod 148. This rod is received in a bore 150, in the block 32, and a setscrew 152 is provided for holding the rod 148, and the shoe-bottom rest 22, in any desired position of vertical adjustment, see Fig. 3. The bottom rest 24 comprises an angle member 155 which is secured to the bottom face of the block 32 by means of screws 156.

The operation of the machine will now be described. The shoe is presented to the machine, bottom side up, by the operator, who inserts the lasting margin of the stock, e. g., the cover C, between the roll 10 and the accurate surface 16 on the sleeve 14, with the treadle 106 elevated and the aforementioned parts in the open position shown in Fig. 4. The shoe is held upwardly with its bottom, e. g., the bottom surface of the platform P, bearing against the shoe bottom rests 22 and 24 and also against the lower end of the roll 10 which is preferably rounded, as shown in Fig. 4. The treadle is now depressed so that the lasting margin of the cover is pressed yieldingly against the helical rib 12 on the roll 10, by the arcuate surface 16 of the sleeve 14, in the manner explained above.

Now, as the roll is rotated, at a relatively high speed by the motor 42, it exerts a frictional drag on the stock tending to feed the shoe along at a rapid rate. By resisting this tendency, which is made possible by the smooth character of the surface of the rib 12, the operator is able to cause the shoe to move along at a slower, yet moderate, rate, so that the peripheral speed of the rib will be considerably greater than the linear speed of the stock, which, as explained above, is held

against the rib. Accordingly, while the shoe is fed along, the helical rib 12 also acts as a screw tending to move the stock axially of the roll 10.

The lead of this rib is such that each successive portion of the stock, as it passes between the roll 10 and the arcuate surface 16 on the sleeve 14, is drawn upwardly by the rib 12 and the stock is thus, continuously and progressively, tensioned in a direction heightwise of the shoe. By permitting the roll to feed the shoe at a faster rate, or by holding the shoe back and further retarding its rate of feed, the action of the helical rib to draw the stock upwardly may be correspondingly modified and the resulting heightwise tension varied to suit different materials or operating conditions, within limits determined by the setting of the spring 86 and the nature of the material.

Referring to Fig. 2, it will be apparent that the lasting margin of the stock is wrapped around the roll, for a considerable extent of its periphery, in a direction extending inwardly from the edge of the bottom of the shoe by the arcuate surface 16 on the sleeve 14. Thus, in addition to its feeding and heightwise tensioning actions, the roll also exerts a stress on the stock tending to draw its lasting margin inwardly from the edge of, and over, the bottom of the shoe.

As the stock, after being tensioned and over-drawn, as above explained, leaves the roll and sleeve, its lasting margin is immediately pressed against the bottom of the shoe, e. g., the bottom face of the platform P, by a rapid series of hammer blows imparted thereto by the vertically reciprocating hammer 18. It will be understood that the inside surface of the lasting margin of the cover C and/or the marginal portion of the bottom face of the platform P, will have previously been coated with a suitable adhesive so that, by the application of pressure thereto by the hammer, the lasting margin will be securely bonded to the platform. Because of the rapidity with which the hammer 18 operates, substantially every portion of the stock will be subjected to its action with the result that the lasting margin is laid very smoothly against the bottom of the shoe.

As the lasting operation is continued, the shoe is positioned, in a widthwise direction, by the edge gage roll 20, which bears against the edge of the platform P, see Figs. 1 and 3. When the lasting operation, which may proceed around the entire periphery of the bottom of the shoe, or along only a portion thereof, as desired, nears completion, and a portion of the lasting margin previously secured to the bottom of the platform is reached, the operator depresses the treadle 16 thus freeing the lasting margin which is then laid down on the platform as the shoe is manually moved past the reciprocating hammer 18.

While the herein illustrated machine has been shown, and its operation described, as performing the so-called "cover-lasting operation," it is to be understood that the machine is designed for, and capable of, lasting the upper of a conventional shoe with like satisfactory results. Accordingly, in this specification, as well as in the appended claims, the term "lasting" is used in a broadened sense, and as now understood in the trade, so as to include not only the conventional lasting operation but also the analogous "cover-lasting operation," while the term "lasting margin" is intended to include that portion of the cover of a platform shoe which corresponds to the

like portion of the upper stock of a conventional shoe.

Having described our invention, what we claim as new and desire to secure by Letters Patent of the United States is:

- 5 1. In a lasting machine, frictionally acting means for continuously and progressively tensioning successive portions of the stock to be lasted, in a direction heightwise of a shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock against said rib, and means for pressing the lasting margin of the tensioned stock against the bottom of the shoe.
- 10 2. In a lasting machine, frictionally acting means for continuously and progressively tensioning successive portions of the stock to be lasted, in a direction heightwise of a shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock against said rib, and means for pressing the lasting margin of the tensioned stock against the bottom of the shoe.
- 15 3. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 20 4. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 25 5. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 30 6. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 35 7. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 40 8. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 45 9. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 50 10. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 55 11. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 60 12. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 65 13. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 70 14. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.
- 75 15. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and provided with a smooth-surfaced helical rib and means having a relatively fixed operating surface for holding the lasting margin of the stock wrapped around the rib, and means for pressing the lasting margin of the tensioned stock against the bottom of the shoe.

shoe, said means comprising a driven roll mounted for rotation about an axis substantially perpendicular to the portion of the bottom of the shoe being operated upon and having a smooth-surfaced helical rib and a member having an arcuate operating surface for holding the lasting margin wrapped around the rib, and means for pressing the lasting margin of the tensioned stock against the bottom of the shoe.

6. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll mounted for rotation about an axis substantially perpendicular to the portion of the bottom of the shoe being operated upon and having a smooth-surfaced helical rib and a member having an arcuate operating surface for yieldingly holding the lasting margin wrapped around the rib, and means for pressing the lasting margin of the tensioned stock against the bottom of the shoe.

7. In a lasting machine, frictionally acting means for continuously and progressively tensioning successive portions of the stock to be lasted, in a direction heightwise of a shoe, and for exerting a stress thereon tending to feed the shoe, and a vertically reciprocating hammer for imparting a rapid series of hammer blows to a substantial area of the lasting margin of the tensioned stock for pressing it against the bottom of the shoe.

8. In a lasting machine, frictionally acting means for continuously and progressively tensioning successive portions of the stock to be lasted, in a direction heightwise of a shoe, and for exerting a stress thereon tending to feed the shoe, said means comprising a driven roll provided with a helical rib and means having a relatively fixed operating surface for holding the lasting margin of the stock against said rib, and means for imparting a rapid series of hammer blows to the lasting margin of the tensioned stock for pressing it against the bottom of the shoe.

9. In a lasting machine, frictionally acting means for continuously and progressively tensioning successive portions of the stock to be lasted, in a direction heightwise of a shoe, and for exerting a stress thereon tending to feed the shoe, said means comprising a driven roll provided with a helical rib and means having a relatively fixed operating surface for holding the lasting margin of the stock against said rib, and a vertically reciprocating hammer for imparting a rapid series of blows to the lasting margin of

the tensioned stock for pressing it against the bottom of the shoe.

10. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, and a vertically reciprocating hammer for imparting a rapid series of blows to a substantial area of the lasting margin of the tensioned stock for pressing it against the bottom of the shoe.

11. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll provided with a helical rib and means having a relatively fixed operating surface for holding the lasting margin of the stock against said rib, and means for imparting a rapid series of hammer blows to the lasting margin of the tensioned stock for pressing it against the bottom of the shoe.

12. In a lasting machine, frictionally acting means for continuously and progressively tensioning successive portions of the stock to be lasted, in a direction heightwise of a shoe, for drawing the lasting margin thereof inwardly from the edge of, and over, the bottom of the shoe, and for exerting a stress thereon tending to feed the shoe, said means comprising a driven roll provided with a helical rib and means having a relatively fixed operating surface for holding the lasting margin of the stock against said rib, and a vertically reciprocating hammer for imparting a rapid series of blows to the lasting margin of the tensioned stock for pressing it against the bottom of the shoe.
